CLAIM

The ornamental design for a mobile phone, as shown and described.

DESCRIPTION

FIG. 1 is a front perspective view of a mobile phone showing our new design in a folded state;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is a top view thereof, shown in a partially opened state;

FIG. 10 is another top view thereof, shown in a further partially opened state;

FIG. 11 is a front perspective view of the mobile phone shown in a fully opened state;

FIG. 12 is a front view of FIG. 11;

FIG. 13 is a rear view of FIG. 11;

FIG. 14 is a left side view of FIG. 11;

FIG. 15 is a right side view of FIG. 11;

FIG. 16 is a top plan view of FIG. 11;

FIG. 17 is a bottom plan view of FIG. 11; and,

FIG. 18 is a rear perspective view of FIG. 11.
